UNITED STATES PATENT OFFICE.

EMIL BAUMBLATT, JR., OF PHILADELPHIA, PENNSYLVANIA.

CUFF OR SLEEVE FOR SHIRTS.

1,383,514.

Specification of Letters Patent.

Patented July 5, 1921.

Application filed March 31, 1920. Serial No. 370,360.

To all whom it may concern:

Be it known that I, EMIL BAUMBLATT, Jr., a citizen of the United States, residing at Philadelphia, in the county of Philadelphia and State of Pennsylvania, have invented certain new and useful Improvements in Cuffs or Sleeves for Shirts; and I do hereby declare the following to be a full, clear, and exact description of the invention, such as will enable others skilled in the art to which it appertains to make and use the same.

My invention relates to cuffs or sleeves for shirts.

Among the objects of my invention are:

To produce a cuff or sleeve that is attached to the remainder of the garment by means of snap buttons and button-holes.

To produce a cuff or sleeve that can be quickly and easily detached from the remainder of the garment when desired, the part remaining on the person having no metal parts, pockets or buttons which might serve as a carrier of germs, thus rendering my improved cuff or sleeve especially suitable for use by physicians, surgeons or any one who may have occasion to work without a cuff or lower sleeve portion.

In the drawings:

Figure 1 is a perspective view of a shirt equipped with my detachable cuff or sleeve.

Fig. 2 is an enlarged side view of my detachable cuff or sleeve showing one means for attaching said cuff and sleeve to a garment.

Fig. 3 is an enlarged section taken along the line 3—3 in Fig. 1 and looking in the direction of the arrow.

Fig. 4 is an enlarged section taken along the line 4—4 in Fig. 1 and looking in the direction of the arrow.

The drawings represent a shirt carrying sleeves 11—11 which are attached in the usual manner. Said sleeves are terminated at or near the elbow, as shown in Figs. 1 and 2, and any convenient number of button-holes, such as 12, are provided close to around the ends of said short sleeves.

My improved detachable sleeve 13 is provided with a pocket 14 along the upper edge thereof. A band 15 is secured along one inside face of said pocket and snap fastening members, such as 16, are attached to said band, said fasteners being equal in number to the number of buttonholes 12 provided in the fixed sleeve portion 11.

A second band 17 is secured along the other inside face of said pocket, and co-oper-

ating snap fastening members, such as 18, registering with said first named snap fastening members, are attached to said band.

For use with my detachable cuff, the lower end of the sleeve is provided with any convenient number of buttonholes, such as 19.

My improved detachable cuff 20 is provided with a pocket 21 along the upper edge thereof. A band 22 is secured along one inside face of said pocket and snap fastening members, such as 23, are attached to said band, said fasteners being equal in number to the number of buttonholes 19 in the detachable sleeve portion 13.

A second band 24 is secured along the other inside face of the pocket 21, and co-operating snap fastening members, such as 25, registering with the snap fastening members 23, are attached to said band.

The method of using my improved cuff or sleeve will now be explained:

The garment being assembled as shown in Fig. 1, either the cuff 20, or the sleeve portion 13, may be detached by separating the proper snap fastening members, which can be readily done by merely pulling the outer side of the pocket outwardly in order to separate the fastening members, thus avoiding the tedious operation of unbuttoning a plurality of buttons which obtains when these pockets are secured together by the ordinary button.

When it is desired to replace the cuff or sleeve on the garment, the buttonhole end of the short sleeve 11, or the buttonhole end of the detachable sleeve portion 13, is inserted into the pocket 14, or the pocket 21, as the case may be, and the snap fastening members 16—18, or the snap fastening members 23—25, respectively, are then gripped through said buttonholes, thus securing the cuff or sleeve to the garment.

I claim:

1. A detachable sleeve portion for shirts, comprising a pocket along the upper edge thereof, a band secured along one inside face of said pocket members of snap fasteners secured to said band, a second band secured along the other inside face of said pocket, co-operating members of said fasteners secured to said second band, registering with said first named members, in combination with a shirt provided with a fixed sleeve portion having a band shaped to fit inside said pocket and provided with holes registering with said members.

2. A detachable cuff for shirts, comprising a pocket along the upper edge thereof, a band secured along one inside face of said pocket, members of snap fasteners secured to said band, a second band secured along the other inside face of said pocket, coöperating members of snap fasteners secured to said second band, registering with said first named members, in combination with a sleeve having a band shaped to fit inside said pocket and provided with holes registering with said members.

In testimony whereof I affix my signature.
EMIL BAUMBLATT, JR.
